PAUL PANHORST AND CHARLES G. PANHORST, OF NEW YORK, N. Y.

BOTTLE-CLOSURE.

1,018,923.

Specification of Letters Patent.

Patented Feb. 27, 1912.

Application filed July 9, 1909. Serial No. 506,752.

To all whom it may concern:

Be it known that we, PAUL PANHORST and CHARLES G. PANHORST, both citizens of the United States of America, and both residing 5 in the city, county, and State of New York, have invented a certain new and Improved Bottle-Closure, of which the following is a specification.

Our invention relates to bottle closures 10 and particularly to metallic cup closures of the "crown cap" style, our object being to provide a simple and efficient opening device therefor.

In the accompanying drawings in which 15 our invention is illustrated, Figure 1 is a side elevation of a bottle top with sealing cap to which our invention is applied in one form; Fig. 2 is a vertical section thereof on the line 2—2, Fig. 1; Fig. 3 is a plan view of 20 a partially formed blank of our improved cap ready to be applied to a bottle; Fig. 4 is a cross section of the opening tongue on the line 4—4, Fig. 2; and Fig. 5 is a similar section through a tongue of modified construc- 25 tion.

The difficulty commonly experienced in removing the well known crown cap from beer bottles or the like is as freely acknowledged as is the superiority of the cap itself 30 as an efficient sealing means. The only satisfactory device now generally in use for this purpose is the stationary opener which is secured as a more or less permanent fixture in all restaurants, cafés, bars, etc., and possesses the requisite strength, rigidity and 35 leverage to permit of a quick removal of the cap. We have found however that the difficulty experienced in the removal of the closure is due in great part to the fact that 40 the greater the stress upon the sealing flange at a single point, the tighter it binds around the sides of the bottle neck since the tendency is for the flange to take on an oval form of less width in its short diameter than 45 that of the original circular cap, thus pressing its indentations the more firmly beneath the annular rim. It frequently happens 50 that the metal of the cap tears across before the flange spreads at the sides enough for its indentations to clear the annular depression in the bottle neck into which they are forced.

We have found that the cap may be readily removed by hand by means of a tongue 55 A of convenient length and relatively broad base B, integral with the cap. To give this tongue the requisite strength we propose to

provide it with straight ribs C which may be formed in any convenient manner but preferably by corrugations which extend from a point sufficiently far down the tongue 60 below the flange to a point well above the indentations D in the flange of the cap and preferably as close to the top of the cap as possible. By forming the ribs in this way the lever action of the tongue is made most 65 effective since its fulcrum point is well above the indentations D, in fact is practically on the top of the bottle neck, while the lever is rigid at the point of greatest strain, viz, at the level of the indentations D. 70 While the tongue is quite effective thus formed, we propose to further reinforce it by making it of a plurality of thicknesses of metal. It will be seen from the partially formed blank shown in Fig. 3 that the 75 tongue blank is slit down the middle. In the form which it takes when the cap is applied to the bottle (Fig. 2), these halves are overlapped. The same result may be accomplished by folding the tongue blank, as 80 indicated by the cross section Fig. 5, in this case a triple thickness of the tongue being secured throughout a portion of its length. The reinforcing thus secured has a secondary and important effect which is disclosed 85 upon pressing the tongue upward to free the cap. As the tongue is lifted the two halves (if the split tongue form is used) slide over each other, with the result that the tongue instead of acting as a single diametral lever, in which capacity it lifts only 90 the indentations d which are formed in the space between the corrugations from the groove in the bottle neck, resolves itself into a pair of simultaneously acting tangential 95 levers, at an angle to each other and tending to pry out the indentations on opposite sides of the cap flange. The same effect is obtained with the folded flange, the middle fold of which acts as a toggle member. This 100 tangential action, which is secured in either construction suggested, obviates the tendency of the cap to tear across at the point where the lever is applied, while minimizing the oval form referred to above, and rendering the removal of the cap a matter of facility and ease. At the same time it is to be noted that the efficiency of the closure is not in the least affected and in fact the same machines now used to adjust the crown cap 110 may with only slight modifications, be employed to adjust the present cap.

We claim as our invention:

1. A metallic cap closure comprising a lateral sealing flange and a split tongue integral therewith, comprising overlying corrugated sections.
2. A metallic cap closure comprising a lateral sealing flange with securing indentations and a split tongue integral therewith, comprising overlying sections provided with 10 corrugations forming ribs extending from a point below said flange to a point above said indentations.
3. A metallic cap closure comprising a lateral sealing flange and a tongue integral 15 therewith comprising overlying sections serving as tangential opening levers, substantially as described.

4. A metallic cap closure comprising a lateral sealing flange and a tongue integral therewith, said tongue being slit longitudinally and the sides thereof folded across each other whereby upon the lifting of said tongue the sides thereof act upon the sealing flange as tangential levers to pry it open, substantially as described. 20 25

In testimony whereof we have signed our names to this specification, in the presence of two subscribing witnesses.

PAUL PANHORST.
CHAS. G. PANHORST.
